[57] CLAIM

The ornamental design for a bicycle anti-lock brake regulator, as shown and described.

DESCRIPTION

FIG. 1 is a front perspective view of a bicycle anti-lock brake regulator showing my new design;

FIG. 2 is a rear perspective view thereof; and,

FIG. 3 is a side perspective view thereof; the opposite

side being a mirror image of that shown.

The undisclosed bottom view is flat and plain.

FIG. 1

FIG. 2

FIG. 3
